UNITED STATES PATENT OFFICE.

AARON F. KEARNS, OF MOSCOW, OKLAHOMA TERRITORY.

HAY-STACKER.

No. 848,832.

Specification of Letters Patent.

Patented April 2, 1907.

Application filed June 4, 1906. Serial No. 320,152.

To all whom it may concern:

Be it known that I, AARON F. KEARNS, a citizen of the United States, residing at Moscow, in the county of Woodward, Oklahoma Territory, have invented certain new and useful Improvements in Hay-Stackers, of which the following is a specification.

This invention appertains to appliances for stacking grain and which are adapted to be operated by horse-power and embody in their construction a supporting-frame and a pivoted fork or carrier for receiving the load and depositing the same upon the stack.

The invention is designed, chiefly, to improve the general structure of the type of apparatus herein stated and admit of the parts being adjusted and readily accessible for repairs or other purpose.

For a full description of the invention and the merits thereof and also to acquire a knowledge of the details of construction of the means for effecting the result, reference is to be had to the following description and accompanying drawings.

While the invention may be adapted to different forms and conditions by changes in the structure and minor details without departing from the spirit or essential features thereof, still the preferred embodiment is shown in the accompanying drawings, in which—

Figure 1 is a perspective view of a stacker embodying the invention. Fig. 2 is a side view thereof. Fig. 3 is a vertical longitudinal section of the stacker, showing the fork or load-carrier elevated. Fig. 4 is a detail perspective view of a portion of the fork or load-carrier, showing more clearly the brace between the adjustable back and longitudinal bar and the means for adjustably connecting said brace to said bar. Fig. 5 is a detail perspective view of the rear posts, showing the upper and lower pulleys and the operating cord or rope passing therethrough.

Corresponding and like parts are referred to in the following description and indicated in all the views of the drawings by the same reference characters.

The framework for supporting the operating parts is constructed in a way to admit of its ready transportation over the ground from one place to another, and preferably comprises runners 1 and transverse connecting-pieces 2. Posts 3 extend upwardly from the front portion of the runners and are provided at their upper ends with rollers 4.

Braces 5 are interposed between the posts 3 and the runners and serve to stay said posts in the direction of movement of the fork. Other braces 6 stay the posts 3 laterally and are connected at their lower ends to the front transverse connecting-piece. Posts 7 project upwardly from the rear of the runners and are supplied at their upper ends with rollers 8 and are strengthened by means of front braces 9 and lateral braces 10. A cross-bar 11 is attached to the upper portion of the posts 7 and has its end portions projected laterally to form stops to limit the outward and rearward movement of the fork or load-carrier. A single roller 12 is provided near the lower end of one of the posts 7 and a pair of rollers 13 are located near the lower end of the opposite post. The posts 3 and 7 are upwardly diverged, this arrangement having been found to give the best results. The fork or load-carrier comprises longitudinal bars 14, which have pivotal connection at their rear ends with the lower ends of the posts 7, said bars being connected near their rear ends by a cross-bar 15 and strengthened by braces 16, the latter being connected at their rear ends to the cross-bar 15 and at their front ends to the longitudinal bars 14 and arranged to extend across the runners and rest thereon so as to support the fork or load-carrier in horizontal position. The cross-bar 15 is likewise adapted to rest upon the runners 1 and materially assist in supporting the fork or load-carrier in horizontal position. The fork proper comprises tines 17, transverse bars 18, and a back-support which is adjustable and pivotally connected to the body of the fork. The cross-bars 15 are spaced apart and constitute a head, and the tines 17 are secured thereto.

The back support embodies a series of fingers 19, which are pivotally connected to the rear portion of the tines 17, a rail 20, and braces 21 between certain fingers 19 and the longitudinal bars 14, said braces having adjustable connection with the bars 14 to admit of varying the inclination of the back support. The rail 20 is preferably attached to two of the fingers only, and to said fingers are connected the braces 21. The remaining fingers are disconnected from the rail 20 and rest thereon when supporting the load. It is to be understood that all the fingers may be attached to the rail 20, if desired. The braces 21 have notches 22 at their lower rear ends to make positive engagement with keep-

ers 23, applied to the bars 14 and prevented from disengagement with said keepers by keys 24, which are slipped into the keepers, so as to confine the braces when moved to the required position. Upon removal of the keys 24 from the keepers 23 the braces 21 may be disengaged from the keepers and move so as to adjust the back support of the rake or load-carrier to any angular position.

10 For actuating the fork or load-carrier cords or ropes 25 are attached to the fork-head and pass upward over the rollers 4, thence over the rollers 8 and around and beneath the rollers 12 and 13 and laterally to make connection with the draft or other power by means of which the stacker is operated. Upon drawing upon the outer ends of the cords or ropes 25 the fork or load-carrier is elevated, the bars 14 turning upon 15 their pivotal connection with the posts 7 and the cords or ropes 25 leaving the rollers 4 after the fork has reached a position above said posts 3. When the fork or load-carrier reaches the limit of its upward and rearward movement, which is determined by a projecting end of the cross-bar 11, the load is delivered upon the stack. A controlling cord or rope 26, having a spring in its length, is connected at one end to the head of the fork and 20 at its opposite end to the front transverse connecting-piece, and as the fork or load-carrier reaches the limit of its upward or rearward movement said controlling cord or rope is subjected to tension by stretching of the spring interposed in the length thereof. Hence after the load has been discharged the fork or load-carrier is started upon its return to normal or horizontal position by the contractile action of the spring in the length of 25 the controlling cord or rope 26. The grain or other product to be stacked is placed upon the fork in any manner and is delivered upon the stack in the manner stated.

40 Having thus described the invention, what is claimed as new is—

1. In a stacker, the combination of a framework comprising runners, pairs of front and rear posts projected upward from the runners, a cross-bar connecting the rear pair of posts near their upper ends and having its end portions projected laterally beyond the said rear posts to form stops, a fork or load-carrier comprising longitudinal bars having pivotal connection with said posts, a cross-bar and braces connecting said longitudinal bars of the fork and adapted to rest upon the runners and support the fork or load-carrier in approximately horizontal position, and means for raising and lowering the said fork or load-carrier.

2. A hay-stacker comprising the following elements in combination, namely, runners, transverse connecting-pieces at opposite ends of the runners, posts projecting upwardly from the ends of the runners and provided at their upper ends with rollers, a pair of braces for each post interposed between the same and the runners and their connecting-pieces, a cross-bar connecting the rear posts near their upper ends and extended to form stops, longitudinal bars pivoted to the rear posts, cross-bars connecting the front portion of the longitudinal bars and forming a rake-head, tines secured to said cross-bars, fingers pivoted to the tines, braces pivoted to certain fingers and having adjustable connection with the longitudinal bars, a rail secured to the fingers with which said braces are connected and forming a support for the remaining fingers, and operating-cords attached to the rake-head and passing over the rollers at the upper ends of the aforesaid posts and adapted to have the operating force applied thereto.

In testimony whereof I affix my signature in presence of two witnesses.

AARON F. KEARNS. [L. S.]
